UNITED STATES PATENT OFFICE.

AANON BENTZEN, OF NEW YORK, N. Y.

SHIP'S RIGGING.

Application filed August 22, 1925. Serial No. 51,830.

This invention relates to sailing vessels and has particular reference to an improved rigging therefor.

The invention consists in an improved rigging for fore-and-aft sailing vessels, particularly schooners, and comprehends a rigging by means of which a rearrangement of the total sail area is had, with a view of obtaining better sailing qualities when traveling to windward and a larger and more effective sail area when running before the wind.

It is a well-known and established fact that a "leg-of-mutton" sail is more efficient than a gaff sail when traveling to windward, and, furthermore, that leg-of-mutton sails have the advantage that in jibbing there is a less area and mass of sail to swing over from starboard to port, or vice versa, and hence the strain to which the boom and sheets are subjected, is minimized. It is, however, obvious that there is a loss of sail area in a leg-of-mutton sail over a gaff sail; and, therefore, the present invention contemplates as a further object, the provision of an improved upper rigging, which in addition to compensating for this apparent loss, affords an auxiliary or supplemental sail area, the combination of which exceeds the sail area of a gaff sail rig.

The invention furthermore and more specifically embodies an upper rigging including a yard on each mast equipped with four triangular sails, namely, two upper top-sails and two lower yard-sails, one of each of which is respectively disposed to starboard and port, whereby the advantage of having a total increased sail area distributed among a greater number of smaller sails is obtained, thus rendering the handling of the rig easier and necessitating a smaller crew in proportion to the total sail area.

Further objects and advantages derived from the improved rigging reside in the attaining of a greater and more efficient driving power when traveling to windward for the reason that yards can be braced farther around than in a square rigged ship; but due to the employment of a larger number of smaller sails, the same can be held more firmly to the wire rope stays, thus affording an excellent opportunity to gain the best driving force therefrom.

The particular rigging furthermore affords an unusually large amount of "cutting edge", and as soon as the wind has exerted its full force against the triangular top and yard

sails of which it is composed, it passes away at the leech without interfering with the luff of the next adjacent sail.

The invention furthermore embodies an improved rigging which affords a larger sail area for light or strong winds, which area is more readily adjustable as well as steadier, and more effectually distributed as a storm rig; a rigging which is easier handled due to the fact that when "tacking" the necessity of lowering the topsails is obviated; an upper rigging provided with means for facilitating the furling or unfurling, thereby entailing economy in time and labor, and a rigging which is comparatively simple, inexpensive and efficient.

With the above recited and other objects in view, reference is had to the following specification, and drawings, in which there is exhibited one example or embodiment of the invention which is in no way intended as a limitation upon the scope of the appended claims as it is to be clearly understood that variations and modifications which properly fall within the scope of said claims may be resorted to when found expedient.

In the drawings—

Fig. 1 is a perspective view of a ship rigged in accordance with the invention and illustrating the sails fully set;

Fig. 2 is a fragmentary perspective view of the rigging at the juncture of the main or lower mast with the topmast;

Fig. 3 is a similar view of the upper portion of the topmast;

Fig. 4 is a front view of the upper rigging with the sails unfurled;

Fig. 5 is a similar view illustrating certain of the sails unfurled and others partially unfurled.

Referring to the drawings by characters of reference, 10 designates the hull of a vessel, 11 the lower or mainmast, and 12 the booms. Main or boom-sails 13 of the leg-of-mutton type are carried by the mainmast and booms, and, if desired, the vessel may be equipped with jibs 14.

The invention resides particularly in the upper rigging, which includes the topmast 15, the yards 16, a pair of triangular shaped starboard and port topsails 17 and 18, and a pair of triangular starboard and port yardsails 19 and 20. The topmast 15 is mounted at its lower end in a topmast step 21 and is also secured at vertically spaced points by clips 22 and 23 to the top of the lower or

- mainmast. The yard 16 is mounted for horizontal and vertical swinging movements in a swiveled summit yoke 24 mounted in an eye-bracket 25 on the lower clip 22. The yard 5 is further supported and braced by vertical stay lines 26, which extend upwardly and are respectively connected to the upper and lower topsail stay arms 27 and 28, the former being pivoted for vertical movement at 29 10 in a hanger 30, which is swiveled at 31 in a bracket clip 32 secured to the upper end of the topmast 15. The latter lower topsail stay arm 28 is pivoted at 32 in a stirrup 33 which is swiveled at 34 in an eye-bracket 35 15 on the top clip 23. The topsails 17 and 18 have their vertical inner edges 36 which form the altitude of the triangle, provided with guide rings 37 threaded upon or embracing the stay-lines 26. The upper end 20 or apex 38 of each sail has connected thereto a rove halyard 39 trained over an outer block 40 and an intermediate block 41 on the upper stay arm 27 for the purpose of raising or unfurling the topsail. The means for 25 spreading the topsails laterally consists of a spreader-line 36^a connected to the outermost point 37^a of each topsail and trained over a guide eye 38^a and around blocks 39^a on the yard 16. 30 In order to provide means for furling the topsails, a clew-line 42 is connected at its upper end to the vertical stay line 26, and each clew-line is trained through the lower guides 43 adjacent the lower edge of the sail, and 35 vertically spaced marginal guides 44 on the outer inclined edge 45 of each topsail. From the uppermost guides 44, the topsail clew lines 42 extend downwardly to the deck. The yard-sails 19 and 20 are suspended 40 from or carried by hoops 46 threaded upon the yard 16, said hoops being attached to the upper horizontal edge 47 of each yard-sail. The yard-sails are hauled outwardly by means of outhaul-lines 48 connected at their 45 upper ends with the outermost hoops 46 and trained around blocks 49 at the outer ends of the yard 16. The outhaul-lines 48 are trained around blocks 50 carried adjacent the medial portion of the yard 16 from 50 whence they lead to the deck.
- The yard-sails 19 and 20 are hauled inwardly or furled by means of buntlines 51 which are connected by bridles 52 to the outer vertical edges 53 of the triangular 55 yard-sails at vertically spaced points. The buntlines are trained around blocks 54 attached to the vertical shrouds 55 of the mainmast 11 from whence they lead to the deck. The apexes or lower ends 56 of the yard-sails 60 are connected by stay-lines 57 to the gunwale of the hull. The yard is limited in its vertical rocking movements by yard topping stays 58, which are connected at their opposite ends respectively to an eye 59 on the top- 65 mast 15 and to the outer end of the yard

with sufficient slack to allow for their vertical rocking movements. The topping stays may be provided with extensions 60 which are run to the deck for topping the yard.

From the foregoing it will be evident that 70 the subdivision of the total sail area into a large number of comparatively small units, renders the setting or taking in and shortening of the sail a much easier task than with the customary rig, consequently a 75 smaller crew can be carried and the difficult task of reefing in heavy weather is avoided since the shortening of the sail can be done entirely by the leads which pass down from the various sails to the belaying pins on the 80 deck.

It will be further noted that more driving efficiency out of the sail spread when going to windward is obtained, for the reason that not only can the yards be braced further 85 around than in a square rig ship, but the system of employing a plurality of small triangular sails held firmly to the wind on wire rope stays, affords an excellent opportunity to obtain the best driving force from these 90 sails.

It will be further observed that by positioning the summit yoke well forward of the mast, it becomes possible to swing the yard 95 with its sails around and trim the sails in the most advantageous manner to catch the wind when the ship is beating to windward.

By means of the rigging disclosed it is obvious that in a seaway with a light breeze, top sails may be carried, while the rigging 100 gives a larger, lighter and stronger wind sail area, more adjustable to conditions, as well as a steadier and better distributed storm rig. In running before the wind, it will be seen that the rigging, due to the additional triangular yard-sail and topsail, gives practically the same amount of canvas as a gaff sail while the remaining topsail and yard-sail, afford two extra sails, thereby increasing the total sail area. 105

The aforementioned advantages are all compared with a schooner which the present rig resembles the most.

If desired, power for hoisting the sails may be employed without in any way departing from the scope of the invention. 115

What is claimed is:

1. A ship's rigging, including a leg-of-mutton mainsail, starboard and port topsails, and triangular depending starboard and port yard-sails, each having the vertical edges disposed outwardly and the inclined edges inwardly. 120
2. In a ship's rigging, the combination with a leg-of-mutton mainsail, a pair of topsails and a pair of yard-sails, each disposed respectively on the port and starboard sides of the topmast, a yard arm from which said topsails and yard-sails are supported, and means of connection between the yard arm 125

and mast to permit of relative horizontal and vertical swinging movements of said yard arm.

3. A ship's rigging, including a main-mast, a topmast, a yard arm supported from the mainmast for horizontal and vertical swinging movements, a mainsail supported from the mainmast, starboard and port topsails supported from the yard arm, and top-mast, and depending starboard and port yard-sails supported from the yard arm, each of said yardsails having the vertical edges disposed outwardly and the inclined edges inwardly.

15 4. The combination with a sailing vessel equipped with leg-of-mutton main-sails, of a top rig including a topmast, a yard arm mounted for vertical and horizontal swinging movement, triangular starboard and port topsails, and triangular depending starboard and port yard-sails having straight outer and upper edges and angular inner edges.

5. In a fore-and-aft rigged vessel, including leg-of-mutton mainsails, boom and mast supporting the same, and a top rigging including a topmast, a yard arm connected to the mast for horizontal and vertical swinging movements, upper and lower yard stay arms connected to the topmast for horizontal and vertical swinging movement, a connection between the free ends of the yard stay arms and the yard arms, means of connection between the free ends of the yard arm

and the topmast for limiting the vertical swinging movement thereof, triangular port and starboard top sails, triangular depending port and starboard yard sails, means for raising and lowering the topsails, and means for spreading and contracting the topsails.

6. In a fore-and-aft rigged vessel, including leg-of-mutton mainsails, boom and mast supporting the same, and a top rigging including a topmast, a yard arm connected to the mast for horizontal and vertical swinging movements, upper and lower yard stay arms connected to the topmast for horizontal and vertical swinging movements, a connection between the free ends of the yard stay arm and the yard arm, means of connection between the free ends of the yard arm and the topmast for limiting the vertical swinging movement thereof, triangular port and starboard topsails, triangular depending port and starboard yard-sails, means for raising and lowering the topsails, and means for spreading and contracting the topsails, said first-mentioned means comprising rove halyards connected with the upper ends of the topsails, said latter means comprising clew-lines connected at their upper ends with the vertical staylines, guides on the topsails through which the clew-lines are trained, and guide means on the upper yard stay arms through which the remainder of the clew-lines are trained and led to the deck.
